COMPARTMENTED JEWELRY TRAY FOR PIERCED EARRINGS

Vincent Di Bartolo, Cresskill, N.J., assignor to
Mele Manufacturing Co., Inc.

Filed Aug. 16, 1974, Ser. No. 498,085

Term of patent 14 years

Int. Cl. D3—02

U.S. Cl. D87—1 B

Fig. 2

Fig. 3

FIG. 1 is a top perspective view of a compartmented jewelry tray for pierced earrings showing my new design; FIG. 2 is a side elevational view thereof; and

FIG. 3 is a bottom plan view.

I claim:

The ornamental design for a compartmented jewelry tray for pierced earrings, as shown.
